UNITED STATES PATENT OFFICE.

THOMAS W. ATTAWAY, OF HART COUNTY, GEORGIA.

DESIGN FOR A REIN-GUIDE BRACKET FOR HAMES.

SPECIFICATION forming part of Design No. 29,242, dated August 16, 1898.

Application filed July 19, 1898. Serial No. 686,373. Term of patent 7 years.

To all whom it may concern:

Be it known that I, THOMAS W. ATTAWAY, a citizen of the United States, residing in Hart county, near Royston, in the county of Franklin and State of Georgia, have invented and produced a certain new and original Design for Rein-Guide Brackets for Hames; and I do declare the following to be a full, clear, and exact description of the invention, such as will enable others skilled in the art to which it appertains to make and use the same.

The invention relates to a new and original design for a rein-guide bracket for hames; and it consists of the configuration shown in the accompanying drawing, in which the figure represents the invention in perspective.

The leading features of my design comprise

the frame 1, consisting of a vertical portion 2, having the laterally-projecting arms 3, connected by the vertical bar 4, forming a rectangular aperture 5, across which are arranged, one above the other, grooved cylindrical bodies 6.

What I claim is—

The design for a rein-guide bracket for hames as herein shown and described.

In testimony whereof I have hereunto set my hand in presence of two subscribing witnesses.

THOMAS W. ATTAWAY.
